UNITED STATES PATENT OFFICE.

HUBERT F. JONAS, OF OSHKOSH, WISCONSIN, ASSIGNOR OF ONE-HALF TO
GUSTAV M. LINDEMANN AND ARTHUR C. SMITH, OF SAME PLACE.

HAND-BAG.

SPECIFICATION forming part of Letters Patent No. 592,988, dated November 2, 1897.

Application filed February 10, 1897. Serial No. 622,832. (No model.)

To all whom it may concern:

Be it known that I, HUBERT F. JONAS, a citizen of the United States, residing at Oshkosh, in the county of Winnebago and State 5 of Wisconsin, have invented certain new and useful Improvements in Hand-Bags; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

My invention relates to improvements in 15 hand-bags, and especially to English bags.

The objects of my invention are, first, to manufacture hand-bags so that the stitching around the frame may be done by machinery; second, to manufacture a bag which is attached to a part of the frame and this afterward secured to another part to complete the frame; third, to manufacture a bag which when finished will have the raw edges of the leather around the frame concealed and the 25 bag present a beautiful appearance; fourth, to provide a stronger and simpler means of attaching the bag to the frame; fifth, to lessen the cost of manufacture.

In the accompanying drawings, Figure 1 is 30 a perspective view, and Fig. 2 a top view, of the bag, it being open. Fig. 3 is a top view, and Fig. 4 a cross-section, of the inlay, showing the method of attaching the bag. Fig. 5 is a vertical section of the frame with the 35 leather portion attached, showing the position when the bag is closed.

Similar letters refer to similar parts in each view.

A is the metallic frame; B, the leather portion of the bag; B', the lining, and C the inlay, provided with perforations c c c, &c., the requisite distance apart to admit of stitching. D D, &c., are the stitched seams attaching the leather portion B and the lining B' to the 45 inlay C. The inlay C is preferably constructed of thin metal, so as to be readily bent around the corners of the bag.

In the method of manufacture the leather portion B and the lining B' are placed upon 50 the inlay-strip and stitched thereto by an ordinary sewing-machine, the stitches passing through the perforations in the inlay, thus

attaching the inlay beneath the leather portion of the bag and the lining. The inlay may be bent in stitching, so as to approximate 55 conform to the shape of the frame.

By reference to Fig. 4 it will be seen that the inlay C is provided with an offset of approximately the thickness of the leather and lining, so that the outside surface of the 60 leather will be on the same plane as the upper surface of the inlay.

By reference to Fig. 5 it will be observed that the frame A is constructed of angle iron, the top leg when the bag is closed being 65 double, so as to form two inclosing strips A A' and providing a recess a between the double strip, into which the inlay, after being attached to the leather portion, is inserted and secured to the frame by the usual rivets 70 used in attaching the trimmings to the bag e e e.

After attaching the bag to the inlay by stitching through the perforations c c c, &c., the inlay can be easily bent to conform to 75 the shape of the frame and inserted between the strips A' A''. An offset a' is provided in the lower strip to correspond with the offset of the inlay.

In English bags heretofore constructed the 80 frame has been in two parts at right angles to each other and braced together, leaving a space between, through which the leather portion and lining are stitched together by hand. In this construction the stitches are 85 not uniform, for the reason that a long stitch is necessary around each brace connecting the two parts of the frame. In the finished product the raw edge of the leather is exposed around the edge of the frame above 90 the stitching, and it is necessary to trim it by hand and in a very particular manner in making high-grade bags. In my invention the bag is first stitched separately to the inlay and the inlay afterward attached to the 95 frame, making the completed frame.

The edge of the leather and also the edge of the lining are inclosed from view between the upper and lower strips of the frame A' A''. No trimming or dressing is necessary 100 and the wear upon the stitches is avoided.

Having thus described my invention, what I claim to have invented, and desire to secure by Letters Patent, is—

1. As an improved article of manufacture, a hand-bag consisting of a body portion of suitable flexible material, a lining therein, an inlay-strip stitched to the edges of said flexible material and lining, frames having flanges to embrace the inlay-strips and the materials stitched thereto to cover the stitching, the said strips being riveted between the said flanges, substantially as described.

2. As an improved article of manufacture, a hand-bag consisting of a body portion of suitable flexible material, an inlay - strip stitched to the edges of said flexible material,

frames having parallel flanges adapted to receive the inlay-strips between them, depending flanges also formed on said frames and adapted to extend interiorly of the bag and means for securing the inlay-strips between said parallel flanges, substantially as described.

In testimony whereof I affix my signature in presence of two witnesses.

HUBERT F. JONAS.

Witnesses:
